UNITED STATES PATENT OFFICE.

WILLIAM I. KENISON AND JESSE A. NEELY, OF NILES, KANSAS; SAID NEELY ASSIGNOR
TO L. B. NICKELS, M. C. PAYNE, AND E. O. NEELY, ALL OF NILES, KANSAS.

MOTOR-PLOW.

1,152,369.

Specification of Letters Patent. Patented Aug. 31, 1915.

Application filed May 2, 1913. Serial No. 765,077.

To all whom it may concern:

Be it known that we, WILLIAM I. KENISON and JESSE A. NEELY, citizens of the United States, residing at Niles, in the county of Ottawa, State of Kansas, have invented certain new and useful Improvements in Motor-Plows; and we do hereby declare the following to be a full, clear, and exact description of the invention, such as will enable others skilled in the art to which it appertains to make and use the same.

This invention relates to certain novel and useful improvements in motor plows.

In carrying out our invention it is our purpose to provide a machine of this class wherein the frame may be maintained level at all times, thereby lessening the strains and load on the power mechanism of the device, and we also provide means whereby the plow or plows proper may be raised and lowered or adjusted to regulate the depth of the furrow, and the angle or pitch at which the plow point enters the ground.

A further object of our invention is to suspend the plow or plows proper from the frame in such manner that the line of draft or pull on said plows is below the axles of the wheels of the frame, and thus the upward strain or pull usually caused by the traction of the motor plow is neutralized so that no dead weight is required at the front of the plow frame to hold the latter down against the upward pull of the plow mechanism at the rear of the frame, and consequently but a minimum expenditure of power is necessary to be employed in propelling the motor trucks.

A further object of our invention is the provision of a machine of this type which will embody in its construction the desired features of simplicity, durability, efficiency and economy, and our machine, embodying as it does, but relatively few parts may be manufactured and marketed at a relatively low cost.

With the above recited objects and others of a similar nature in view, our invention consists in the construction, combination and arrangement of parts set forth in and falling within the scope of the appended claim.

In the accompanying drawings: Figure 1 is a view in side elevation of a motor plow embodying our invention. Fig. 2 is a top plan view. Fig. 3 is a rear view. Fig. 4 is a vertical longitudinal sectional view

taken on the line 4—4 of Fig. 2. Fig. 5 is a vertical cross sectional view taken through the rear of the machine on the line 5—5 of Fig. 2. Fig. 6 is a view taken through the front of the machine on the line 6—6 of Fig. 2. Fig. 7 is a detail perspective view of the brackets of the front post of the machine. Fig. 8 is a perspective view of the plow supporting bail arranged at the rear of the machine.

Referring now to the accompanying drawings in detail, the letter A indicates the main frame of the device as an entirety, the latter comprising a substantially rectangular frame, including longitudinal side bars 70 1—1, the rear cross bar 2 and the front cross bar 3. The front end of the frame is formed with an extension, including the inclined bars 4 terminating at their outer ends in the U-shaped section 5. The rear axle is 75 shown at 6 and carries the rear ground wheels 7, while the front axle is illustrated as at 8 and is provided with front ground wheels 9. Mounted on the frame, preferably just forward of the rear axle, is a platform 10 carrying a suitable motor M, the shaft 11 of which is provided with a sprocket 12 over which runs the endless drive wheel chain 13 which drives the sprocket wheel 14 and the differential gear G carried by the 80 cross shaft 15 journaled transversely in the frame. Each end of this shaft 15 is provided with a sprocket wheel 16, and over these sprocket wheels run endless drive chains 17 which pass around the relatively 85 large circular sprocket wheels 18 bolted to the spokes 19 of the rear wheels 7. Thus it will be seen that the machine is driven from the motor through the train of power mechanism just described.

The front axle has pinned thereto a collar 19' to which the lower end of the vertical post 20 is connected, this post extending upward through the U-shaped bracket 21 bolted in the extension 5 at the front of the frame. To steer the machine, any suitable means may be employed, and in the present instance we provide a steering post 22, carrying at its upper end the wheel 23, the lower end of said post passing through a sleeve 24 bolted to the frame, and is connected at its lower end with a short curved arm 25, to which is pivoted the adjacent end of the rod 26, the forward end of said rod being pivotally connected at 27 to the bell crank lever 110

- 28, one arm of the bell crank lever 28 being fulcrumed at 28' on the front axle, the opposite arm of the lever having pivoted thereto as at 29 one end of the rod 30, which extends parallel to the front axle and is connected at its opposite end at 31 to the lever 32, fulcrumed at 33 on the front axle.
- The plow proper of the machine is indicated at P, and may be of any desired form.
- 10 The usual curved beam of the plow is shown at 34, and the plow is suspended from the main frame by means of a bail 35, the ends 36 of which are loosely bolted at 37 to the side bars 1 of the frame, so that the bail is 15 pivotally mounted. At the center of the bail we provide the spaced lugs 38 which embrace the beam 34 and hold the plow against sidewise movement. The forward end of the plow beam 34 is connected by 20 bolts 40 to the adjacent ends of the diverging brace bars 41, the forward ends of these bars being connected to the cross rod 42 adjacent the ends thereof, this rod 42 extending between the lower ends of the vertically 25 depending bars 43 which are bolted at their upper ends at 44 to the side bars 1 of the frame. Adjacent the central portion thereof are the inner ends of the parallel rods 45, which extend upwardly and forwardly, and 30 at their outer ends are connected by means of the short transverse rod 46. This rod 46 is loosely connected to the lower end of the vertical link post 47, the upper end of this link being pivoted at 48 to the outer end of 35 the lever 49, this lever being pivoted at 50 to the axle post 20. The handle end 51 of the lever 49 is within easy reach of the operator at the seat S, this seat being mounted upon the seat support 52, bolted at .53 to 40 the platform 10. The lever 49 is provided with the usual pivoted hand grip 54 and the pawl operating rod 55, the pawl 56 of which is designed to engage with the toothed segment 57 passing at the upper end of the 45 post 20. This lever 49 is used for raising and lowering the front end of the frame, for it will be seen that as the forward end of the frame is slidably mounted on the post 20 by means of the bracket 21, and as the 50 transverse rod 46 is mounted at its ends in the parallel sides of the U-shaped extension 5 of the frame, and as this transverse rod is connected by means of the parallel rods 45 with the cross bar 42, connecting the 55 depending vertical bars 43 which are attached to the frame, upon the downward movement of the lever 49 the link 47 will be pulled upward and consequently the frame of the machine will be lifted at the front end.
- 60 In order to raise and lower the plow we mount upon the rear end bar 2 of the frame a rock shaft 58, one end of which is connected with the shaft arm 59, while 60 65 designates a link pivoted at 61 to the arm, and as at 62 to the lug 63 fastened to the

70 plow beam near the lower end thereof. A semi-circular rack 64 is mounted on the rear end of the frame and extends over the rock shaft, while 65 indicates a lever connected to the rock shaft at 66, this lever being provided with the usual locking pawl 67 and the operating rod 68 therefor. It will be seen that the pawl may be raised and lowered and the levers actuated to move the rock shaft.

75 For the purpose of leveling the frame according to the surface of the ground over which the machine travels, we secure rigid to one of the side bars 1, a segmental rack 69, while fast with the axle 6, is a collar 70 forming the lower end of the lever 71. This lever is provided with the usual locking pawl 72 operated by the rod 73. It will be noted that as the ends of the rear axle 6 are 80 bent into a crank frame as shown at 6', the axle being mounted in the bearing boxes 74, when the lever 71 is operated, the axle will be rocked or rotated to move the crank portions thereof carrying the wheels to the desired position, and the axle may be locked 85 in such position by means of the locking pawl of the lever, and therefore the frame may be leveled as conditions require. By so leveling the frame the strain on the power mechanism is greatly reduced.

90 For the purpose of taking up slack on the drive chains 17, we provide for each a chain tightener, one of which is shown at T in Fig. 1. This tightener consists of a depending arm 75, the end of which carries a star wheel 76 which is designed to have the chain run thereover, while 77 designates a tension spring connected at one end to the arm 75 and at the opposite end to the adjacent side bar or frame. It will be seen that the pull 95 of the spring on the arm 75 tends to draw the star wheel against the chain and thereby maintain the latter properly tight.

100 The front axle is further braced or supported in connection with the main frame by means of the reach rods 78 pivoted as at 79 to the front axle connected as at 80 to the arms 81 depending from the underside of the platform 10.

110 From the above description, taken in connection with the accompanying drawings, the construction and operation of our improved motor plow will be readily apparent to those skilled in the art.

115 It will be noted that we have provided means whereby the frame may be not only raised or lowered at the front end thereof to give the proper pitch to the plow for entering and running in the ground, but said frame may be leveled at will and in addition thereto the plow itself may be raised and lowered by the means heretofore described to regulate the proper depth of the furrow.

120 While we have herein shown and de-

scribed one particular embodiment of our invention, we wish it to be understood that we do not confine ourselves to all the precise details of construction herein set forth by way of illustration, as modification and variation may be made without departing from the spirit of the invention or exceeding the scope of the appended claim.

What we claim is:

- 10 In a motor plow, the combination with a frame, of a front axle and a rear axle and a pair of wheels rotatably mounted on each axle, a post connected with the front axle and swiveled in the forward end of the frame, propelling mechanism, a plow suspended from the frame between the rear wheels thereof, said plow including a forwardly extending plow beam, connecting

members between the forward end of the plow beam and the frame, connecting 20 rods attached to said connecting members at one end, a transverse rod extending between and connected with the connecting rods, a link attached at one end to said transverse rod, and a lever pivoted 25 to the post and connected at its forward end to the link, said lever being adapted to raise and lower the forward end of the frame and regulate the pitch of the plow.

In testimony whereof, we affix our signatures, in the presence of two witnesses.

WILLIAM I. KENISON.
JESSE A. NEELY.
